COMBINATION DOOR

John S. Murphy, San Gabriel, Calif.

Application September 28, 1937, Serial No. 166,149

9 Claims. (Cl. 24—38)

This invention relates to building construction, and more particularly to doors of the type commonly spoken of in the trade as "combination" or "all-weather" doors.

5 An object of the present invention is to provide an improved design for a door of the general character described, wherein a sash is slidably mounted in such a manner that it is adapted to be slid optionally into a pocket in the lower portion of the door, wherein the sash is concealed and protected by suitable panels, or into closing relation within an opening in the upper part of the door. The present invention, therefore, represents an improvement over that forming the 15 subject matter of Patent No. 1,935,887 issued to me on November 21, 1933.

More specifically, an object of the present invention is to provide an improved and simplified construction for supporting and retaining the 20 panels in spaced, parallel relation, whereby greater strength and rigidity are imparted, not only to the panels themselves, but to the entire door, offering assurance against spreading of the stiles and racking of the door.

25 A further object in this same connection is to provide means for facilitating assembly of the door, in the form of a guide which aids materially in disposing the upper edges of the panels accurately in proper position with respect to the lock rail by which they are to be engaged.

Another object is to reduce the over-all cost of the door assembly by providing a lock rail constructed entirely of sheet metal stampings and of such design that it needs no mortising to mount it rigidly in operative position upon the stiles.

35 A further object is to provide improved and simplified means for mounting a screen frame within the opening of the door whereby the screen frame is removably retained by a locking device 40 releasable from the inner side of the door only.

45 Yet another object is to provide improved means of interengagement between the lower edges of the panels and the bottom rail, and efficient means for draining any moisture which might otherwise accumulate within the bottom of the sash-receiving pocket.

It is a further object of the present invention to provide a door construction of the general character described which is relatively simple and inexpensive to manufacture and which is altogether superior in efficiency, durability, serviceability and convenience.

The invention possesses other objects and advantageous features, some of which, with those 50 enumerated, will be set forth in the following de-

scription of the preferred embodiment of my invention which is illustrated in the drawings accompanying and forming a part of the specification. It is to be understood that I do not limit myself to the showing made by the said drawings and description, as I may adopt variations of the preferred form within the scope of my invention as set forth in the claims.

Referring to the drawings:

Fig. 1 is an elevational view showing the inside 10 face of a door embodying the principles of the present invention;

Fig. 2 is a transverse, vertical, sectional view taken upon the line 2—2 of Fig. 1, with the direction of view as indicated. This figure is highly 15 enlarged, but broken away at certain portions to reduce its size, and shows the sash raised to its closing position;

Fig. 3 is a view similar to Fig. 2, but showing the sash lowered to its concealed, or inoperative 20 position;

Fig. 4 is a horizontal, sectional view taken through one of the stiles of the door upon the line 4—4 of Fig. 2, with the direction of view as indicated;

Fig. 5 is a view similar to Fig. 4, taken, however, upon the line 5—5 of Fig. 2, with the direction of view as indicated;

Fig. 6 is an enlarged view in horizontal section, taken upon the line 6—6 of Fig. 1, to show the 30 manner of interconnection between the top rail and stile;

Fig. 7 is a view similar to Fig. 6 showing the 35 manner of interconnection between the bottom rail and stile, upon the line 7—7 of Fig. 1, with the direction of view as indicated;

Fig. 8 is an enlarged detail view in elevation, showing an improved type of lock for retaining the screen frame in operative position. The direction of view may be considered to have been 40 taken as indicated by the arrow 8 of Fig. 3;

Fig. 9 is a transverse, vertical sectional view taken through the lower portion of a door and showing a slightly modified form of interconnection between the panels and the bottom rail. 45

The door of the present invention comprises vertical stiles 11 spaced apart and joined by a top rail 12 and bottom rail 13. The rectangular space defined by these members is divided into upper and lower openings 16 and 17 respectively, 50 by a lock rail 18, the construction of which is one of the important features of the present invention.

This lock rail is preferably constructed of sheet metal stampings and comprises a pair of channel 55

shaped members 19 and 20. These channels 19 and 20 are rigidly and permanently mounted in spaced, parallel relation by means of a plate 21 at each end of the lock rail, against which the 5 end of the channels 19 and 20 abut and to which they are preferably welded to provide an integral construction. The end plates 21 provide the means for mounting the lock rail 18 in operative position upon and extending between the opposed 10 stiles 11. A screw 22 extends through a suitably positioned hole in each plate 21 and is driven into the inner edge of the stile to fasten the lock rail 18 rigidly in position. Preferably the screw hole in each plate 21 is adjacent the upper 15 edge thereof, so that access to the screw 22 can be had more conveniently, it being remembered that the screw driver must be inserted between the two channels 19 and 20, in order to mount the lock rail 18 in position.

20 Thus it may be seen that efficiently operating means are provided for mounting the lock rail without the necessity of forming a mortised joint between the rail and the stiles. No accurate fitting is required other than to make sure that 25 the length of the lock rail coincides with the distance between the stiles, but in spite of this saving in time and labor required for the assembly of these parts, a considerably more rigid construction is provided because of the great degree 30 of strength that can be established by attaching the end plate 21 to the stile by means of wood screws. Because of the integral connection between the channels 19 and 20 and the end plates 21, spreading of the stiles is definitely prevented, 35 thus overcoming one of the principal deficiencies of most all-purpose doors wherein the elements of the lock rail are mortised and glued to the stiles. In this type of door the mortised joint is necessarily quite small, hence the repeated shocks 40 to which the door is subjected during normal use frequently break the bond between the rail and stiles and causes the joint to work loose, thus permitting the stiles to spread. Similarly, being constructed of two spaced, parallel channel members 45 each of which is possessed of considerable strength, the lock rail is proof against wracking, i. e., twisting of one end with respect to the other. Hence, by firmly connecting the end plates 21 of the lock rail to the stiles substantially 50 midway between the ends of the latter, a considerable degree of similar strength is imparted to the entire door construction, thus reinforcing it against wracking or twisting strains.

55 In order to make it possible optionally to open or close the upper opening 16, the slidable sash 26, comprising a frame 27 mounting a pane 28 of glass or similar material, is mounted for vertical sliding movement upon and between the stiles 11. For this purpose a suitable channel 27 (see 60 Fig. 4) is formed in the inner edge of each stile 11, this preferably being provided by securing stops 29 and 29' to the inner edge of each stile 11, though it should be understood that the same construction can also be provided by routing out 65 the inner edge, leaving beads spaced apart sufficiently to provide the channel 27 of desired width. The channel 27 of each stile 11 extends preferably throughout the entire length thereof, thus making it possible to slide the sash 26 past the lock rail 18. Hence, when it is desired to close 70 the upper opening 16, the sash 26 is raised and when it is desired to open the opening 16 the sash is lowered into a pocket 31 which is defined by two spaced, parallel panels 32 which extend 75 across the lower opening 17. The upper edge of

each of these panels 32 is seated within the associated channel 19, 20 of the lock rail. The parts are so positioned that a nice fit is established between the panels and the channels; and in order to provide a smooth guide way for the sash 5 26, the inner face of each panel 32 is rabbeted as indicated at 33, and the inner flange 34 of the associated channel is disposed within the rabbet thus formed. By utilizing this construction, the thickness of the flange is equal to or slightly less than the thickness of the panel, the importance 10 being that all obstructions to upward movement of the sash between the two channels 19 and 20 are avoided. Toward this same end, preferably the lower edge of the inner flange 34 of each 15 channel is beveled, as indicated at 36.

It should be observed that the inner flange 34 of each channel is materially longer than the outer flange 37. This is to facilitate assembly of the device. When inserting the upper edge of a 20 panel 32 into the associated channel, the parts are merely placed in such position that the upper edge of the panel rests against that portion of the inner flange 34 which projects beyond the bottom edge of the other flange 37. This will 25 insure such registry of the panel with the channel that the two may then be pressed toward each other, causing the upper edge of the panel to enter the socket or recess until the top edge of the panel engages the web 38 of the channel. Were 30 both flanges of the same length, difficulty would be encountered in securing such registry, inasmuch as the panels would have the tendency to move inward beyond the plane of the inner flange 34, thus making it impossible for the edge of 35 the panel to enter the recess.

Whereas the two channel members 19 and 20 are of similar construction, they differ from each other in that the channel 20, which is proximal to the outer face of the door, is provided with an 40 upstanding flange 41 which extends from adjacent the intersection of the web 38 and the outer flange 37. This upstanding flange 41 serves as a retainer for the bottom edge of the screen frame 42, a substantially complementary slot 43 45 being formed in the bottom of the screen frame for that purpose. The screen frame 42 is preferably fitted within the upper opening 16, thus making it necessary to move the upper edge of the screen frame 42 outwards, away from the 50 plane of the door, before the lower edge of the screen frame can be elevated sufficiently to cause disengagement of the upstanding flange 41 from the slot 43. To prevent such outward movement of the upper edge of the screen frame 42 55 until removal of the screen frame is desired, a lock 46, operable from the inner side of the door only, is mounted upon the inner face of the screen frame 42 adjacent the upper edge thereof. This lock comprises two plates 47 and 48, the latter 60 of which has its edges offset toward the plate 47 so as to dispose the body of the plate 48 far enough away from the plate 47 to provide a chamber 49 between the plates 47 and 48 within which a locking disc 51 is mounted for rotary 65 movement. Preferably the plates 47 and 48 also are substantially disc-shaped and are mounted by means of a plurality of screws 52 extending through the edges of the plates 47 and 48, in such position that the center of the disc 51 is disposed 70 closer to the upper edge of the screen frame 42 than the radius of the disc. The two stationary plates 47 and 48 are cut away or relieved so that a flat side of each lies substantially in the plane 75 of the upper edge of the screen frame. The ro-

tary disc 51 also is provided with a flat side 53, so that by turning the disc 51 the flat side 53 can be brought into registry with the flat side of the two stationary plates under which circumstance 5 the upper edge of the screen frame is free to move outward away from the door. However, by turning the disc 51, the flat side 53 can be moved downward into the recess 49, causing a segment of the disc 51 to extend upward into a 10 rabbet 54 which is formed on the inner face of the outer bead 56 which defines the channel 51 in the under side of the top rail 12 into which the top of the sash 26 extends when raised. The necessity for seating the locking portion of the 15 disc within the rabbet 54 arises from the desirability of leaving the inner face of the screen frame 26 smooth, so as to avoid obstructions to adjustment of the sash. Because of this, the entire locking device 46 is rabbeted into the inner face of the screen frame, so that the plate 47 lies flush with the inner surface of the screen frame.

A central opening 61 is provided in the plate 47 and through this opening a boss 62, which is 25 formed centrally upon the movable disc 51, projects. This boss is provided with a screw driver kerf 63 which is accessible inside the door when the sash 26 is lowered. This type of lock is of exceedingly simple and inexpensive construction, 30 consisting of only three plates or discs and the screws necessary to anchor the outer discs 47 and 48 to the screen frame. It is exceedingly small and compact and cannot get out of order; and yet it operates with great efficiency in retaining 35 the screen frame against inadvertent displacement.

In order to retain the sash 26 at selected elevation, I have provided a spring pressed ratchet 66 in the form of a detent 67 extending through 40 that channel member 19 which is associated with the inner face of the door so that its beveled end 68 projects into the space between the two channels and through which the sash 26 extends. This detent 67 carries a head 69 which can be 45 engaged by the finger nails when it is desired to withdraw the detent 67 from engaging position against the action of the leaf spring 71 whereby the detent 67 is mounted upon the lock rail and continuously urged inward to operating position. 50 Cooperating abutments for the detent 67 are conveniently provided by a plurality of notches 72 which are disposed at suitably spaced intervals in the inner face of one of the stiles 11 of the sash 26. The height at which the sash 26 will be 55 retained by the rabbet is determined by which of the notches 72 receives the detent 67.

The vertical edges of the two panels 32 are seated within the grooves 76 formed in the inner edges of the stiles 11 from the lock rail 18 downwards, glue preferably being used in order to strengthen the entire construction. The means of interconnection between the lower edges of the panels 32 and the bottom rail 13 is preferably a strip 81 of thickness corresponding to the thickness of the bottom rail 13 and having a pair of opposed depending flanges 82 rabbeted into the upper edge of the bottom rail 13 so that their outer faces lie flush with that of the bottom rail. In the upper edge of this strip 81, two spaced, 70 parallel grooves 83 are provided for the reception of the lower edge of the panel 32. Weep holes 84 extend downward from the bottoms of the channels 83 leading to the outer face of the door at 86. Preferably an additional weep hole 87 leads 75 downward through the upstanding portion be-

tween the two channels 83, so that moisture which otherwise would collect within the bottom of the pocket 31 can be drained without its having to seep into the bottom of either of the channels 83. It is important to note that these weep holes lead 5 not to the bottom edge of the door, as in customary practice, but to the lower face of the door, thus reducing the tendency for water dripping from the weep holes to run back over the sill to the inside of the door.

Cushions 91 are provided upon the strip 81 between the two panels 32 in position to be engaged by the sash 26 when in its lowermost position. The same screws 92 which fasten the cushions 91 upon the strip can be used to screw the 15 strip 81 in position by using screws long enough to pass all the way through the strip into the bottom rail 13.

Fig. 9 illustrates a slightly modified form of the strip 96, this being the form utilized when the 20 strip is composed of metal instead of wood, as in the case of the previously described strip 81. With this modification, the inner faces of the panels 32 are engaged by the spaced upstanding flanges 97, the space 98 between these upstanding 25 flanges provides a convenient socket for the reception of the cushions 99 which are so shaped that they can be anchored in operative position by being pressed into this space 98.

Whereas any suitable type of interconnection 30 between the rails 12 and 13 and stiles 11 can be utilized, I prefer that they be both mortised and dowelled. Fig. 6 shows one of preferably a plurality of dowels 101 interconnecting the top rail 12 with one of the stiles 11 in addition to the regular mortise and tenon joint 102 commonly employed. Fig. 7 also shows one of a plurality of dowels 103 which is employed in addition to the double mortised and tenoned joint 104, whereby the bottom rail 13 is connected to each of the 40 stiles 11.

A plurality of anti-rattling springs is preferably employed pressing the sash against the outermost stop 29'. These springs 111 are carried by the inner face (i. e., that face which is proximal to the sash) of the innermost stop 29, and are preferably disposed within a groove 112 there provided, so that when the springs are depressed they lie entirely within the groove 112 instead of projecting beyond the surface in which that 45 groove is formed. The importance here is that a perfectly smooth guide rail for the sash 26 is provided, all projections which otherwise might interfere with vertical adjustment of the sash being eliminated.

I claim:

1. In a door construction, a pair of spaced stiles, top and bottom rails, a lock rail dividing the space defined by said rails and stiles into upper and lower openings, a pair of panels closing 60 said lower opening and spaced apart to define a pocket therebetween, said lock rail comprising a pair of metal channels inverted to receive the upper edge of one of said panels in each, and means fastening the ends of said channels to 65 said stiles.

2. In a door construction, a pair of spaced stiles, top and bottom rails, a lock rail dividing the space defined by said rails and stiles into upper and lower openings, a pair of panels closing 70 said lower opening and spaced apart to define a pocket therebetween, said lock rail comprising a pair of metal channels inverted to receive the upper edge of one of said panels in each, a plate at each end of said lock rail and rigidly attached 75

to the associated ends of said channels to retain them in spaced, parallel relation, and means for fastening said plates to said stiles to mount said lock rail in position and to hold said stiles against spreading.

3. In a door construction, a pair of spaced stiles, top and bottom rails, a lock rail dividing the space defined by said rails and stiles into

upper and lower openings, a pair of panels closing said lower opening and spaced apart to define a pocket therebetween, said lock rail comprising a pair of end plates fastened to said stiles and a pair of spaced, parallel channels each fastened at one end to one of said plates and each of said channels comprising a web and a pair of spaced flanges extending downward therefrom and embracing the upper edge of one of said panels therebetween, the inner flange of each of said channels being longer than the

20 outer to guide the associated panel when being inserted into the channel.

4. In a door construction, a pair of spaced stiles, top and bottom rails, a lock rail dividing the space defined by said rails and stiles into upper and lower openings, a pair of panels closing said lower opening and spaced apart to define a pocket therebetween, said lock rail comprising a pair of end plates fastened to said stiles and a pair of spaced, parallel channels disposed upon opposite sides of said sash each fastened at one end to one of said plates and each channel comprising a web and a pair of spaced flanges extending downward therefrom and embracing the upper edge of one of said panels therebetween, the inner face of each of said panels being rabbeted along its upper edge, and the inner flange of the associated channel being seated therein to provide a joint between said flange and panel free of obstruction to movement of said sash.

40 5. In a door construction, a pair of spaced
stiles, top and bottom rails, a lock rail dividing
the space defined by said rails and stiles into
upper and lower openings, a pair of panels clos-
ing said lower opening and spaced apart to de-
45 fine a pocket therebetween, said lock rail com-
prising a pair of metal channels inverted to re-
ceive the upper edge of one of said panels in
each, a plate at each end of said lock rail and
rigidly attached to the associated ends of said
50 channels to retain them in spaced, parallel re-
lation, and means for fastening said plates to
said stiles to mount said lock rail in position and
to hold said stiles against spreading, and means
on the upper edge of said bottom rail providing
55 spaced, parallel channels within which the lower
edges of said panels are seated.

6. In a door construction, a pair of spaced stiles, top and bottom rails, a lock rail dividing the space defined by said rails and stiles into upper and lower openings, a pair of panels closing said lower opening and spaced apart to define a pocket therebetween, said lock rail comprising a pair of metal channels inverted to receive the upper edge of one of said panels in each, a plate at each end of said lock rail and rigidly attached to the associated ends of said channels to retain them in spaced, parallel relation, and means for fastening said plates to said stiles to mount said lock rail in position and to hold said stiles against spreading, and means on the upper edge of said bottom rail providing spaced, parallel channels within which the lower

edges of said panels are seated, said channel-providing means comprising a strip extending between said stiles along the upper edge of said bottom rail, downwardly extending flanges on the bottom of said strip rabbed into said bottom rail, said strip having spaced, parallel grooves in its upper face within which the lower edges of said panels are seated.

7. In a door construction, a pair of spaced stiles, top and bottom rails, a lock rail dividing the space defined by said rails and stiles into upper and lower openings, a pair of panels closing said lower opening and spaced apart to define a pocket therebetween, said lock rail comprising a pair of metal channels inverted to receive the upper edge of one of said panels in each, a plate at each end of said lock rail and rigidly attached to the associated ends of said channels to retain them in spaced, parallel relation, and means for fastening said plates to said stiles to mount said lock rail in position and to hold said stiles against spreading, and means on the upper edge of said bottom rail providing spaced, parallel channels within which the lower edges of said panels are seated, and said channel-providing means having weep-holes therein leading from the bottom of said channels to the outer face of said door.

8. In a door construction, a pair of spaced stiles, top and bottom rails, a lock rail dividing the space defined by said rails and stiles into upper and lower openings, a pair of panels closing said lower opening and spaced apart to define a pocket therebetween, said lock rail comprising a pair of metal channels inverted to receive the upper edge of one of said panels in each, a plate at each end of said lock rail and rigidly attached to the associated ends of said channels to retain them in spaced, parallel relation, and means for fastening said plates to said stiles to mount said lock rail in position and to hold said stiles against spreading, and means on the upper edge of said bottom rail providing spaced, parallel channels within which the lower edges of said panels are seated, and said channel-providing means having weep-holes therein leading from the bottom of said channels and from the bottom of said pocket. 30 35 40 45

9. In a door construction, a pair of spaced stiles, top and bottom rails, a lock rail dividing the space defined by said rails and stiles into upper and lower openings, a pair of panels closing said lower opening and spaced apart to define a pocket therebetween, said lock rail comprising a pair of end plates fastened to said stiles and a pair of spaced, parallel channels disposed upon opposite sides of said sash each fastened at one end to one of said plates and each channel comprising a web and a pair of spaced flanges extending downward therefrom and embracing the upper edge of one of said panels therebetween, an upstanding flange formed on one of said channels adjacent the intersection of its web and one of its panel-engaging flanges, a screen frame disposed within said upper opening, means on the bottom of said screen frame seating behind said upstanding flange to hold it against outward movement without first raising said screen frame, and releasable locking means holding said screen frame against upward movement. 50 55 60 65 70

JOHN S. MURPHY
